UNITED STATES PATENT OFFICE.

WILLIAM DAN THROOP, OF NORWICH, CONNECTICUT.

ELECTRIC SWITCH.

1,393,649.

Specification of Letters Patent.

Patented Oct. 11, 1921.

Application filed April 6, 1920. Serial No. 371,690.

To all whom it may concern:

Be it known that I, WILLIAM D. THROOP, a citizen of the United States, and a resident of Norwich, in the county of New London and State of Connecticut, have invented a new and Improved Electric Switch, of which the following is a full, clear, and exact description.

This invention relates to improvements in electric switches, and more particularly to an improved construction of pendent switch, an object of the invention being to provide such a switch with a longitudinally movable slide member which, when operated, causes the switch controlling devices to quickly move from one position to another.

A further object is to provide an improved construction of pendent switch embodying certain elements of my improved electric switch disclosed in my application for patent, Serial Number 337364, filed November 11, 1919.

With these and other objects in view the invention consists in certain novel features of construction, and combinations and arrangements of parts, as will be more fully hereinafter described and pointed out in the claims.

In the accompanying drawings—

Fig. 1 is a view in elevation with the casing removed.

Fig. 2 is a view in longitudinal section on the line 2—2 of Fig. 1.

Fig. 3 is a view in longitudinal section through the casing showing in elevation the opposite side of the structure illustrated in Fig. 1.

Fig. 4 is a view in transverse section on the line 4—4 of Fig. 2, but showing the casing in position.

1 and 2 represent the two halves of a supporting block A which may be of porcelain or any other suitable non-conducting material, and these blocks are held in proper relation to each other by means of transverse pins 3.

It is, of course, to be understood that while I have illustrated the supporting block as of two parts, it may constitute a single integral part if desired, and I shall, for convenience of description, refer to the supporting block as a single part.

The block A is provided at its respective ends with pairs of spring contacts 4 spaced apart and electrically connected with binding posts 5 on the ends of the blocks. These

contacts 4 are preferably made of spring strip metal secured at one end and at their other ends bent upon themselves and forming spring tongues 6 having angular bent portions 7 forming flared entrances for contact blocks 8, the latter mounted on a sliding plate 9.

The plate 9 is preferably of fiber or other non-conducting material and is provided on its inner face with a bracket 10. This bracket 10 is movable in a recess 11 in the supporting block A and the latter is also made with a transverse opening 12 communicating with said recess. The bracket 10 has inwardly projecting lugs 13 and 14 at its respective ends and a bail 15 at its free end, which constitutes its intermediate portion, is positioned between the lugs 13 and 14 and is adapted when swung from one position to the other, to move the plate 9 longitudinally.

The bail 15 is provided at its ends with laterally projecting trunnions 16 which are positioned in the ends of recesses 17 and pivoted therein. A transversely curved plate 18 is mounted to slide in a longitudinal groove 19 in the outer face of the block A and through this plate 18 the shank 20 of my improved sliding button 21 is projected and may be secured if desired. The inner end of the shank 20 is connected by a coiled spring 22 with the free end of the bail 15 so that when the button is moved longitudinally from one position to the other, it will, through the medium of the spring 22, throw the bail from one extreme position to another as will be readily understood.

The block A is of general cylindrical form and can be conveniently inclosed in a two part cylindrical casing B of the general size and shape employed in connection with the ordinary type of pendent switch. The ordinary pendent switch has the push button in its end, whereas with my improved switch the sliding button 21 is at the side. The lower end of the casing B is closed and the upper end of the casing is open, as shown at 23, for the passage of the wires (not shown) connected to the terminals or binding posts 5.

The sliding plate 9 is held against possibility of lateral displacement by means of enlargements 24 on the block A and the terminals 5 are carried by angle brackets 25, the latter secured to the block A by means of screws 26, said screws also operating to clamp the electric contacts 4 in proper

position as said contacts 4 may constitute extensions or fixed parts of metal plates 27 located under the angle brackets 25.

The casing B is provided with a longitudinal slot 28 through which the shank 20 of the button 21 projects and is movable, and it will be noted by reference to Fig. 2, that the lugs 13 and 14 are spaced apart a distance sufficient to permit of a certain amount 10 of pivotal movement of the bail 15 without operating the plate 9. Hence, the plate is not moved until the button 21 is moved far enough to place the spring 22 under tension and the spring, as it contracts, will quickly 15 throw the switch from open to closed position and vice versa.

The operation is as follows: When the button 21 is moved from one position to another, its first operation is to swing the end 20 of the spring 22 past the pivotal connection of the trunnions 16 in the ends of the recesses 17, and in so doing, the spring will be put under tension and will quickly swing the bail 15 to its other extreme position. This 25 movement of the bail 15 will cause the plate 9 to move longitudinally by reason of the fact that the bail engages the bracket 10, or more particularly the inwardly projecting lugs 13 and 14 on the bracket. When the 30 plate 9 is in one extreme position, the contact blocks 8 will be in engagement with the contacts 4, and as the latter are of spring metal, a wiping contact engagement is assured at each operation to insure a perfect 35 closing of the electric circuit.

When the plate 9 is moved to its other extreme position, it is moved out of engagement with the contacts 4 and, as above explained, said contacts are in the form of 40 spring tongues with angular portions 7 providing flared entrances for the blocks 8 so as to guide the parts into proper engagement at all times.

Various slight changes might be made in 45 the general form and arrangement of parts described without departing from the invention, and hence I do not limit myself to the precise details set forth, but consider myself at liberty to make such changes and 50 alterations as fairly fall within the spirit and scope of the appended claims.

I claim:

1. A pendent switch, comprising a supporting block of non-conducting material, 55 two pairs of electric contacts on said block, a sliding plate of non-conducting material guided on the block, contact blocks carried by the plate and movable into engagement with the contacts, a sliding button having 60 longitudinal movement relative to the block and at one side thereof and having spaced relationship to the block, a pivoted bail engaging the plate, and a spring connecting the free end of the bail with said button.

65 2. A pendent switch, comprising a sup-

porting block of non-conducting material, two pairs of spring contacts supported on the block, a longitudinally movable plate guided on the block, said plate of non-conducting material, contact blocks on the plate 70 movable into and out of engagement with the contacts, said supporting block having a transverse opening, a bail pivotally supported in the walls of said opening and at its intermediate portion engaging the plate, 75 a sliding button having longitudinal movement relative to the block and at one side thereof and having spaced relationship to the block, and a spring connecting the free end of the bail with said button. 80

3. A pendent switch, comprising a supporting block of non-conducting material, two pairs of spring contacts supported on the block, a longitudinally movable plate guided on the block, said plate of non-conducting material, contact blocks on the plate 85 movable into and out of engagement with the contacts, said supporting block having a transverse opening, a bail pivotally supported in the walls of said opening and at its intermediate portion engaging the plate, 90 a sliding button having longitudinal movement relative to the block and at one side thereof and having spaced relationship to the block, a spring connecting the free end of the bail with said button, a bracket fixed to said plate, and lugs on the bracket spaced 95 apart and between which the bail has a limited independent movement.

4. A pendent switch, comprising a supporting block of general cylindrical form and of non-conducting material, a sliding plate of non-conducting material guided in its movement against one face of the block, a pair of spring contacts on the block having 100 flared entrances into the space between them, contact blocks on the plate movable through said entrances into engagement with the contacts when the plate is moved in one direction, terminals on the ends of the supporting block electrically connected to said contacts, and a slide button having longitudinal movement relative to the block and at one side thereof and having spaced relationship to the block for moving said 105 plate. 110

5. A pendent switch, comprising a supporting block of general cylindrical form and of non-conducting material, a sliding plate of non-conducting material guided in 115 its movement against one face of the block, a pair of spring contacts on the block having flared entrances into the space between them, contact blocks on the plate movable through said entrances into engagement with the contacts when the plate is moved in one direction, terminals on the ends of the supporting block electrically connected to said contacts, a bail pivotally supported in the block 120 and engaging the plate, a button supporting 125 115

103

- plate movable against the outer face of the block, a slide button having longitudinal movement relative to the block and at one side thereof and having spaced relationship 5 to the block, a shank on the slide button projecting through said last-mentioned plate, and a coiled spring connecting the shank and the free end of the bail.
6. A pendent switch, comprising a supporting block, two pairs of contacts on the supporting block, a sliding plate on the supporting block, contact blocks on the plate movable into and out of engagement with the first-mentioned contacts when said 10 plate is moved longitudinally, a casing inclosing the supporting block, said casing having a longitudinal slot in one side there- of, a slide button on the outside of the casing, a shank on the button projected through said slot, and means operatively connecting 20 the shank with the slide plate.
7. A pendent switch, comprising a supporting block, contacts on the block adjacent the ends thereof and at one side of the block, a casing inclosing the block, a member carrying contacts adapted to be moved into and out of engagement with the first-mentioned contacts, and a button projecting outside of the casing at one side thereof and movable longitudinally of the casing and 25 30 operatively connected to said movable member.

WILLIAM DAN THROOP.
